ATTY.

UNITED STATES PATENT OFFICE.

ERICH HAUSDORF, OF BERLIN, GERMANY.

TELEPHONE-RECEIVER.

1,359,061.

Specification of Letters Patent. Patented Nov. 16, 1920.

Application filed November 7, 1919. Serial No. 336,527.

To all whom it may concern:

Be it known that I, ERICH HAUSDORF, a citizen of the German Reich, residing at Berlin, Germany, have invented and

5 useful Improvements in Telephone-Receiver, of which the following is a specification.

This invention relates to a new type of telephone receiver which may be put onto the ear and prevents all noises from without 10 from penetrating to the same. Hence the new receiver is suitable for use in noisy places and is especially adapted for the reception of military commands. A demand has long existed for an army receiver which 15 completely cuts off the auditory duct from communication without while leaving the hands disengaged and allowing the user of the instrument to move with perfect freedom.

20 Contrivances for deaf persons are known consisting of a hearing tube with an elongated part that enters the auricle, and telephone receivers are known having an outer portion which embraces the shell of the ear 25 and clings fast to it.

By the present invention a device is produced in which these two features are combined, the device consisting of a telephone receiver having one member which incloses 30 the electrical portion and the diaphragm of the instrument, and which also enters the auricle or shell of the ear, and a second member which embraces or surrounds the receiver and the shell of the ear, thus enabling the receiver to perch upon the ear. By this combination the auditory duct is subjected solely to the action of the electromagnetic members of the receiver and is 35 completely shut off from external noises; the receiver clings to the ear even if severely shaken, the inner part of the receiver which enters into the auricle, and the outer por-

tion, which embraces the ear, coöperating so as to effectually bring about this result. Hence the person using the receiver has both 45 his hands free.

A manner of carrying out the invention is illustrated in the drawing in which—

Figure 1 is a front elevation

Fig. 2 a rear view and

Fig. 3 a section of the receiver on the line I—I of Fig. 2.

The inner part of the receiver comprises the casing *h*, the coil *g* and the diaphragm *f* and abuts at one side against a cover *n* 55 which has an opening *m*. The cover *n* is furnished with a flange-shaped extension *n*¹ by which the cover *n* is attached to the external finishing piece. The finishing piece consists of the parts *a* and *a'*, the part *a* 60 having an opening *b*. The cover *n*, the extension *n*¹ and the part *a* inclose a space *e*. The internal and external parts of the receiver are held together by screws *p* and *q*. The electrical connections are contained 65 in *k*.

On the receiver being placed on the ear the inner cover of the receiver enters the auricle or shell of the ear and the shell is embraced by the parts *a*, *e*.

70

I claim:

In a telephone receiver, an electrical member, a diaphragm, a primary covering-member adapted to inclose the electrical member and the diaphragm and to enter the shell of the ear, and a secondary covering member adapted to embrace the receiver and the ear round-about so as to cling to the latter and to more effectively convey the sound into the air and exclude extraneous sounds from 80 the ear.

In testimony whereof I have signed my name to this specification.

ERICH HAUSDORF.
